DESIGN FOR SUNGLASSES

Leo Strauss, New York, N. Y.

Application February 11, 1938, Serial No. 75,047

Term of patent 7 years

To all whom it may concern:

Be it known that I, Leo Strauss, a citizen of the United States, residing at New York city, in the county of Queens, State of New York, have invented a new, original, and ornamental Design for Sunglasses, of which the following is a specification, reference being had to the accompanying drawing forming part thereof.

In the drawing,

Fig. 1 is a perspective view of the sunglasses showing my new design.

Fig. 2 is a fragmentary top view of the sunglasses.

I claim,

The ornamental design for sunglasses as shown.
LEO STRAUSS.
